UNITED STATES PATENT OFFICE

DAVID S. JACOBUS, OF JERSEY CITY, NEW JERSEY, ASSIGNOR, BY MESNE ASSIGNMENTS, TO FULLER LEHIGH COMPANY, A CORPORATION OF DELAWARE

FURNACE WALL

Original application filed January 31, 1924, Serial No. 689,610. Divided and this application filed June 30, 1925. Serial No. 40,487.

My present invention is a division of application Serial No. 689,610, filed January 31, 1924, and relates to improvements in furnace walls in connection with which metallic supports may be used. The invention will be best understood from the following description and the annexed drawings, in which Fig. 1 is a view, partly in section, looking at the end of the wall; Fig. 2 is a sectional plan view of Fig. 1; Fig. 3 is a side view of the wall; Figs. 4 and 5 are enlarged details; Fig. 6 is a front view of a boiler furnace partly in section and partly broken away, and Fig. 7 is a section along the line *a—a* of Fig. 6.

In the particular arrangement which I have illustrated, the wall 13 rests against a plurality of vertical members shown as channels 41 which are fixed, thus forming fixed supports. The wall is provided at intervals with special tile 42, each projecting from the wall to a channel 41, as shown best in Figs. 1 and 2. The special tile 42 may be connected to the channels 41 so as to permit the wall 13 to move in any direction in relation to the fixed channels 41. The particular arrangement illustrated comprises a member 43, preferably metallic, having downwardly projecting portions 44 engaging in suitable notches in the side of the tile 42, the member 43 being Z-shaped, with its upwardly extending leg 43^a engaged by a U-shaped clip member 43' having a notch 43'' engaging one of the legs 41' of the channel 41. It will be seen that the clip member holding the connecting member 43 to the support is formed of two substantially parallel and vertical legs joined by a semi-cylindrical portion, and that the notch 43'' in which the leg 41' is received, extends circumferentially of this semi-cylindrical portion and terminates in a portion extending axially of the cylinder. As will be seen by an inspection of Figs. 4 and 5, when the wall 13 moves vertically relatively to the members 41, the clip member 43' will slide along the leg 41' of the channel; when the wall 13 moves horizontally, the upwardly projecting leg 43^a of the member 43 can slide laterally through the clip 43'.

The connection between the clip 43' and the member 43 will also permit relative vertical motion be-

tween the wall and the channels even if the clip 43' is fastened to the channel. The same may be true of the connection between the tile 42 and the member 43, though preferably the projecting portions 44 will engage their notches tightly. The members 43' may also be readily disconnected from the connecting members 43 by merely sliding them a relatively short distance along the channel.

By making the upwardly extending leg 43^a of the member 43 very wide, as shown best in Fig. 2, it will be obvious that no great care will be needed as to the horizontal spacing of the special tiles 42, since such tile may be considerably to one side or the other of the channel 41 and yet the member 43 can be connected to the channel by the clip member 43' and the end of the wide tile 42 will rest against the channel. This enables the building of the wall without the cutting of any of the bricks of the wall, even if such bricks are not of the width for which the spacing of the channels 41 is designed.

A plate 45, which is preferably insulated on the outside to prevent undue heat loss, covers the outer parts of the channels 41 to form a duct between the plate 45 and the exterior of the wall 13, such duct including not only the spaces between the channels 41, but also the spaces between the exterior of the wall 13 and the channels themselves.

It will be understood that the arrangements which I have described are merely illustrative and that the embodiments of my invention may be widely varied.

I claim:—

1. In a furnace, a wall, a support, and a connection between said wall and support comprising a member having substantially parallel legs joined by a portion of approximate semi-cylindrical shape.
2. In a furnace, a wall, a support, and a connection between said wall and support comprising a member having substantially parallel legs joined by a portion of approximate semi-cylindrical shape having a circumferentially extending slot.
3. In a furnace, a wall, a support, and a connection between said wall and support comprising a member having substantially

parallel legs joined by a portion of approximate semi-cylindrical shape having a circumferentially extending slot terminating in an axially extending portion.

4. In a furnace, a wall, a support, a Z-shaped connector between the wall and support, and a U-shaped holding member connecting the connector and support.

5. In a furnace, a wall, a support, a Z-shaped connector between the wall and support, and a U-shaped holding member slidably holding said connector against said support.

6. In a furnace, a fixed support, a wall spaced from said support and having a tile projecting therefrom towards the support, a connecting member on said tile and movable in a vertical direction with respect to said tile, and a holding member joining said connecting member to said support and movable vertically and horizontally with respect to said connecting member.

7. In a furnace, a fixed support, a wall spaced from said support and having a tile projecting therefrom towards the support, a connecting member on said tile and movable in a vertical direction with respect to said tile, a holding member joining said connecting member to said support and movable vertically and horizontally with respect to said connecting member, and, vertically with respect to said support.

8. In a furnace, a fixed support, a wall spaced from said support and having a tile projecting therefrom towards the support, a Z-shaped connecting member on said tile and having one of its legs extending vertically, and a U-shaped holding member having one leg engaging said vertical leg of said connecting member and the other leg engaging said support.

9. In a furnace, a fixed support, a wall spaced from said support and having a tile projecting therefrom towards the support, a Z-shaped connecting member on said tile and having one of its legs extending vertically, a U-shaped holding member having one leg engaging said vertical leg of said connecting member and the other leg engaging said support, and means permitting relative vertical movement between said tile and said connecting member.

10. In a furnace, a fixed support and a wall adjacent thereto, a connecting member mounted on said wall and adapted to move vertically thereon, and a holding member engaging the connecting member and the support and adapted to move vertically on the support.

11. In a furnace, a fixed support and a wall adjacent thereto, a connecting member mounted on said wall and adapted to move vertically thereon, and a holding member engaging the connecting member and the support and adapted to move vertically on the

support, the connecting member adapted to move horizontally with respect to the holding member.

12. In a furnace, a fixed support, a wall adjacent thereto and comprising a tile extending toward the support and having a notch therein, a connecting member movably mounted on said tile and having a part received in said notch to guide the member in its movement on the tile, and a holding member having sliding engagement with said support and said connecting member.

13. In a furnace, a wall, a channel fixed adjacent the wall and having a leg substantially parallel thereto, a member mounted on said wall and having a leg extending adjacent the leg of said channel, and a U-shaped clip slidably mounted on the channel leg and adapted to engage the leg of the member on said wall.
